UNITED STATES PATENT OFFICE.

OTTO OESTERLEN AND KARL CONRAD MÜLLER, OF ZWEIBRÜCKEN, GERMANY.

GAS-BURNER.

1,164,854.

specification of Letters Patent. Patented Dec. 21, 1915.

Application filed April 1, 1915. Serial No. 18,631.

To all whom it may concern:

Be it known that we, OTTO OESTERLEN and KARL CONRAD MÜLLER, subjects of the King of Bavaria, both residing at Zweibrücken,

5 Palatinat, Bavaria, Germany, have invented certain new and useful Improvements in Gas-Burners, of which the following is a specification, reference being had therein to the accompanying drawing.

10 The present invention relates to improvements in gas burners for blast stoves and other intermittently working heat recuperators where up to the present the most simple arrangements have been used.

15 A great deal of the inconveniences connected with the older burners, where the whole burner or mixing chamber has to be swung out when put out of work, are avoided with this invention, the burner being now so constructed that only a small part of the burner has to swing out.

20 As only a part of the burner has to be removed and can be replaced by a closing plate during the blast period of a stove, it is possible to build the immovable part of the burner in such a way as to obtain the best conditions for a rapid and most efficient mixture of gas and air, and also for the best regulation of gas and air admission. The 25 admission of gas and air is regulated by a conical or otherwise shaped valve placed in the immovable part of the burner.

25 This invention provides therefore an apparatus which is not only a convenient and practical means of shutting off the gas when putting the stove on blast, but as the main part of the burner remains fixed, it is possible to build this part so as to obtain an efficient gas and air mixture and at the same 30 time send quickly large quantities of gas into the stove where it is completely burned. With this new burner it is not only easier to change the stove from gas to blast, but also 35 will the heating period be much shorter the 40 efficiency being better than before.

45 Where as formerly the gases were throttled down before entering the copper apparatus, where they mixed with the combustible, this invention transforms the pressure of the gas current in speed by means of the conical valve which forms a main part of this invention. The high speed of the gas then draws in the necessary combustion air in one or two steps.

50 In the drawing: the figure shows a central 55 sectional view of the gas burner. In this

drawing the gas is shown entering the burner from the top, naturally any other position is possible, this depending only from the position of the main gas pipe.

The outer case "a" which is strongly supported or suspended in a fixed distance of the copper stove carries inside through the shaft "d" and ribs "e" a conical valve "b" which can be either advanced or drawn back by wheel and rack "c".

In the drawing the valve "b" is shown closed viz., the burner is out of work. The valve conus is pressed on the mouthpiece "f" and the admission of gas therefore cut off.

When working valve "b" is in the position marked by dotted lines, so that gas can pass from the twyer "i" to the combustion chamber "o". Through the special form of the valve "b" and the mouthpiece "f" the flow of the gas is changed in velocity when leaving the casing "a" and by this velocity combustion air is drawn in, primary and secondary combustion air behind the gas outlet.

In the drawing the primary air is entering through the ring channel "g" while the necessary secondary air enters behind the part "h" by channel "k", being drawn in either by the aspiration of gas current or by the chimney draft of the copper. Movable shutters "l" or "m" allow the regulation of the air inlets.

It is important that the burner mouthpiece "i" is divided into several parts and that when putting the burner out of work a part of it can be swung out or removed, so as to close the copper opening by a plate "p." It is best to combine the removable part of the burner and this cover plate "p" as shown on the sketch. At the end of the heating period, when the copper stove must be closed air tight, the gas is shut off by advancing valve "b," the movable part is swung around the spindle "r" and closed by plate "p" which is screwed tightly on to the part "h."

An exact regulation of both gas quantity and velocity and therefore of the air quantity thereby drawn in is warranted by the chosen form of the conical valve "b." Ordinary valves, gate valves used up to now on burners are inadequate because they get easily choked up with dust and further they liberate relatively large sections when opened slightly, whereas the chosen form of

the valve "b" allow a very delicate regulation and also the admission of any amount of gas to the cowper.

The inside of the mouthpiece "f" and the valve "b" can be cleaned from dust which deposits during work by pressing the valve on to its seat and turning it around several times.

Should an excess of air be required inside the burner "y" air can be admitted by the valve "b" which can be made hollow, the admission being regulated by a slotted ring "s." The gas enters under pressure the casing "a" and that by the transformation of pressure in velocity combustion air is drawn in. Naturally the opposite proceedings are possible, viz. that air is blown in under pressure by the ring channel or the hollow shaft "d" and thus the gas drawn in. The compressed air could also be introduced in the casing "a" and its static energy changed by a corresponding form of the burner into dynamic energy, by which then the gas would be drawn in either through the ring channel "g" or the hollow valve.

Having now particularly described and ascertained the nature of our said invention and in what manner the same is to be performed, we declare that what we claim is:

1. A gas burner for hot blast stoves and other heating chambers having a casing within a fixed distance of the stove, a twyer for conducting the gas from the casing to the stove, said twyer being divided into sections,

a spindle mounted on the periphery of the twyer, a cover plate and one said section mounted on said spindle whereby the plate and section may be swung about the spindle and the stove supplied with gas or closed to the atmosphere.

2. A gas burner for hot blast stoves and other heating chambers having a casing within a fixed distance of the stove, a twyer for conducting the gas from the casing to the stove, said twyer being divided into sections, a spindle mounted on the periphery of the twyer a cover plate and one said section mounted on said spindle whereby the plate and section may be swung about the spindle and the stove supplied with gas or closed to the atmosphere, and a valve within the casing controlling the flow of gas as described.

3. A gas burner having a perforated casing, a longitudinal shaft therein, a valve on said shaft to control the flow of gas, a twyer separable into movable parts, a cover plate fixed on one of said movable parts and hinged on the periphery of said twyer and adapted to cut off the flow of gas through said twyer.

In testimony whereof we affix our signatures in the presence of two witnesses.

OTTO OESTERLEN.

KARL CONRAD MÜLLER.
